(57) **CLAIM**

The ornamental design for a “sanitary storm and catch basin trap”, as shown and described.

DESCRIPTION

FIG. 1 is an assembled oblique view of the sanitary storm and catch basin trap;

FIG. 2 is an oblique view thereof with the fish mouth portion detached from the trap portion;

FIG. 3 is a front view of both the trap portion and the fish mouth portion;

FIG. 4 is a right side view of both the fish mouth portion detached from the trap portion;

FIG. 5 is a left side view of both the fish mouth portion detached from the trap portion;

FIG. 6 is a top view of both the fish mouth portion detached from the trap portion;

FIG. 7 is a rear view of both the fish mouth portion detached from the trap portion; and,

FIG. 8 is a bottom view of both the fish mouth portion detached from the trap portion.
